UNITED STATES PATENT OFFICE.

SIMON TOFFLER, OF NEW YORK, N. Y., ASSIGNOR TO ANNA TOFFLER AND FRANK WARNECK, BOTH OF SAME PLACE.

FLOOR-MAT.

SPECIFICATION forming part of Letters Patent No. 295,839, dated March 25, 1884.

Application filed December 13, 1883. (No model.)

To all whom it may concern:

Be it known that I, SIMON TOFFLER, of the city, county, and State of New York, have invented certain new and useful Improvements 5 in Floor-Mats, of which the following is a specification.

This invention has reference to improvements in floor-mats of that class which are made of a series of transverse slats that are 10 connected by hinge-joints, so that the mats can be readily rolled up whenever it is desired to clean the floors or remove the mats; and the invention consists of a floor-mat made of a series of transverse slats which are connected by U-shaped wire staples, the shanks of which are passed through holes of the slats. 15 The staples are provided with eyes and an intermediate abutment at one end, said eyes being in one plane with the shanks of the staples, while the other ends are bent into eyes at 20 right angles to the plane of the shanks, so as to connect with the eyes of the staples of the next adjoining slat.

In the accompanying drawings, Figure 1 represents a plan of my improved floor-mat. Fig. 25 2 is a plan partly in section of a portion of the same drawn on a larger scale. Fig. 3 is an end view, partly in vertical transverse section, of Fig. 2; and Fig. 4 shows detail views 30 of two forms of staples employed for connecting the slats.

Similar letters of reference indicate corresponding parts.

In the drawings, A A represent a series of 35 wooden slats, of round or other cross-section, which are connected at two or more points by means of U-shaped wire staples B, the shanks of which are passed through diametrical holes a of the slats A. The staples B are provided 40 at one end with eyes b b and an intermediate bent section, b', which latter abuts against the slat A when the shanks d d of the staples B are passed through the holes a a of the slat A. The eyes b b and the abutment b' of the staples 45 B are bent in such a manner that they are in the same plane with the shanks of the staple.

To connect the staples B B of one slat with

the staples of the adjoining slat A, the shanks d d are first passed through the perforations a a and then bent at their ends at right angles 50 to the shanks, the bent ends being inserted through the eyes b b of the staples B of the next slat and then clinched, so as to close up and form connecting-eyes e e at right angles to the plane of the staples B. The eyes e e of the staples of one slat form thus a hinge-connection with the eyes b b of the staples of the next adjoining slat, so that the floor-mat can be quickly rolled up whenever it is desired to remove it from the floor for cleaning the latter 60 or for other purposes. As each staple forms two eyes, the lateral shifting of the slats is entirely prevented. The staples B are bent into shape by a suitable machine devised for this purpose, the ends of the staples being also 65 bent and clinched, so as to form the eyes e e, by machines specially constructed for this purpose.

By making the staples in the shape shown in Fig. 4 and preparing the slats by boring 70 the holes the floor-mats can be quickly assembled and furnished at low rates, so as to be specially applicable for many purposes for which cheap mats are required.

Having thus described my invention, I claim 75 as new and desire to secure by Letters Patent—

The combination of a series of transverse slats having diametrical holes with U-shaped wire staples, the shanks of which are passed through said holes, and provided at one end 80 with eyes and an intermediate abutment and at the other end with eyes at right angles to the plane of the shank, the eyes of the staples of one slat connecting with the eyes of the staples of the adjoining slats, substantially as and 85 for the purpose set forth.

In testimony that I claim the foregoing as my invention I have signed my name in presence of two subscribing witnesses.

SIMON TOFFLER.
